UNITED STATES PATENT OFFICE.

MAURICE E. BENAS, OF NITRO, WEST VIRGINIA.

OAR-PROPELLED VEHICLE.

1,321,030.

Specification of Letters Patent.

Patented Nov. 4, 1919.

Application filed January 24, 1919. Serial No. 272,946.

To all whom it may concern:

Be it known that I, MAURICE E. BENAS, a citizen of the United States, residing at Nitro, in the county of Kanawha and State 5 of West Virginia, have invented certain new and useful Improvements in Oar-Propelled Vehicles; and I do hereby declare the following to be a full, clear, and exact description of the invention, such as will enable others skilled in the art to which it appertains to make and use the same.

My invention relates to improvements in toys running on wheels and intended to simulate boats propelled by oars, and called 15 by me "row-abouts."

My invention will be more clearly understood after reference to the accompanying drawings, in which:—

Figure 1 shows a central vertical section 20 through the vehicle, parts being shown in elevation.

Fig. 2 is a plan view of the complete device.

Fig. 3 is a rear view of the complete device.

Fig. 4 is a detail showing the steering wheel as seen from the front, and on a larger scale than in the other figures.

Fig. 5 shows a section along the line 5—5 30 of Fig. 1, and looking in the direction of the arrows; and

Fig. 6 shows a section along the line 6—6 of Fig. 1, and looking in the direction of the arrows.

35 A represents the body of the vehicle which is in the form of the hull of a boat, having the bottom a preferably of wood, the sides a' preferably of sheet metal, the forward covering or forecastle deck a^2 , the stern post a^3 and the after deck a^4 . The thin metal sides a' are preferably reinforced with wooden boards a^5 , which with the sides a' are slotted at a^6 , see Fig. 1.

B represents the seat having the back B' 45 which is shown in Fig. 2 as slatted.

C represents a cross piece which supports the axle D on which the driving wheels E are journaled, and F represents a stern post to which the yoke G is pivoted, and in which 50 yoke the stern wheel H is journaled. This yoke is provided with a drum g and with a pin g' projecting into the annular groove f' on the reduced portion f of the stern post F. The yoke G is thus rotatably mounted 55 upon the lower end of the stern post F.

Passing over the drum g is the steering

rope or chain I, the two ends of which lead forward and are connected to the opposite ends of the lever K secured fast to the spindle L. To the upper end of this spindle 60 the foot lever M is secured; thus by pressing on one end or the other of the foot lever M the steering rope I swings the drum g and with it the steering wheel H in one direction or the other as desired.

65 The vehicle is propelled by two oars P and P', which have handles p projecting inward through the slots a^6 and are prevented from displacement in said slots by means of the shoulder p' and the pins p^2 , 70 see Fig. 6. These oars are free to slide in the slots a^6 and are thus held in the operative position against longitudinal displacement.

75 These oars P and P' are connected by the connecting rods Q and Q' to the pins q and q' carried by the driving wheels E. These pins q and q' are preferably set at different angles relative to each other on the wheels E, so that the oars will not both at any time 80 be on a dead center.

In order to add a further interest to the toy for children, its intended users, I provide a battery R mounted on the shelf a^6 in the forward portion of the vehicle, and a 85 headlight S controlled by the switch T, see Fig. 1. I may also provide an electric bell U controlled by the push button V. Instead of an electric bell, any other kind of bell may be used if desired.

90 The operation of the device is as follows:

The child climbs in the boat and seats himself on the seat B, placing his feet against the ends of the foot lever M and, 95 grasping the handles p of the oars, moves the oars backward and forward rotating the wheels E and causing the vehicle to either go ahead or astern as he may wish; thus the apparent effect being that he is moving the 100 boats by pulling on the oars, which apparently engage the air only. The child may either flash his light, or keep it constantly going, or he may ring the signal bell whenever desired.

105 The toy may be large enough to have two children on the seat B, each one pulling an oar, but one child only should act as helmsman. One or more passengers may be carried on the rear deck a^4 .

110 It will thus be seen that I provide a vehicle which may be apparently propelled by

oars and may be steered in any desired direction, and in which flash lights or sound signals may be given if desired.

It will be obvious that the headlight and bell may be mere dummies or may be omitted altogether.

It will also be obvious that various modifications might be made in the herein described apparatus, and in the construction, combination and arrangement of parts which could be used without departing from the spirit of my invention, and I do not mean to limit myself to such details except as particularly pointed out in the claims.

Having thus described my invention what I claim and desire to secure by Letters Patent of the United States is:—

1. A toy of the character described, comprising a hull provided with oppositely disposed slots in the sides thereof and a seat, an axle mounted transversely of said hull with driving wheels journaled thereon, a yoke swiveled beneath said hull with a steering wheel journaled therein, a drum carried by said yoke, a double lever pivoted beneath the boat and having steering ropes connected to the ends thereof and passing around said drum, with means propelled by the feet of the driver for swinging said double lever, and thus swinging said steering wheel, oars projecting through said slots, pins secured to said driving wheels, and connecting rods connecting said pins and said oars, substantially as and for the purpose described.

2. A toy of the character described, comprising a hull provided with oppositely disposed slots in the sides thereof and a seat, an axle mounted transversely of said hull with driving wheels journaled thereon, a yoke swiveled beneath said hull with a steering wheel journaled therein, a drum carried

by said yoke, a double lever pivoted beneath the boat and having steering ropes connected to the ends thereof and passing around said drum, with means propelled by the feet of the driver for swinging said double lever, and thus swinging said steering wheel, oars projecting through said slots, with means for holding said oars against longitudinal displacement relative to said slots, pins secured to said driving wheels, and connecting rods connecting said pins and said oars, substantially as and for the purposes described.

3. A toy of the character described, comprising a hull provided with oppositely disposed slots in the sides thereof, and a seat, an axle mounted transversely of said hull with driving wheels journaled thereon, oars projecting through said slots, pins secured to said driving wheels, and connecting rods connecting said pins and said oars, a steering wheel pivotally mounted beneath the hull near the rear end thereof, and means operable by the feet of the driver for swinging said steering wheel laterally, substantially as and for the purposes described.

4. A toy of the character described, comprising a hull provided with oppositely disposed slots in the sides thereof and a seat, an axle mounted transversely of said hull with driving wheels journaled thereon, oars projecting through said slots, with means for holding said oars against longitudinal displacement relative to said slots, pins secured to said driving wheels, and connecting rods connecting said pins and said oars, a steering wheel pivotally mounted beneath the hull near the rear end thereof, and means operable by the feet of the driver for swinging said steering wheel laterally, substantially as and for the purposes described.

MAURICE E. BENAS.
